(57) **CLAIM**

The ornamental design for a cellular phone holder, as shown and described.

DESCRIPTION

FIG. 1 is a perspective view of a cellular phone holder showing my new design;

FIG. 2 is an exploded view of the cellular phone holder of FIG. 1;

FIG. 3 is a front view of the cellular phone holder of FIG. 1; FIG. 4 is a left side view of the cellular phone holder of FIG. 1;

FIG. 5 is a right side view of the cellular phone holder of FIG. 1;

FIG. 6 is a top plan view of the cellular phone holder of FIG. 1;

FIG. 7 is a bottom plan view of the cellular phone holder of FIG. 1;

FIG. 8 is a rear view of the cellular phone holder of FIG. 1; FIG. 9 is a perspective view of a cellular phone holder showing an alternate configuration of my design;

FIG. 10 is a perspective view of a cellular phone holder showing another alternate configuration of my design; and, FIG. 11 is a perspective view of a cellular phone holder showing another alternate configuration of my design.
